UNITED STATES PATENT OFFICE.

EDWARD C. NEWTON, OF MARYSVILLE, CALIFORNIA.

INDICATING-GOVERNOR.

1,201,492.

Specification of Letters Patent. Patented Oct. 17, 1916.

Application filed March 23, 1915. Serial No. 16,490.

To all whom it may concern:

Be it known that I, EDWARD C. NEWTON, a citizen of the United States, and a resident of Marysville, Yuba county, California, have invented certain new and useful Improvements in Indicating-Governors, of which the following is a specification.

This invention relates to devices for controlling the flow of a fluid through a conduit, and more specifically to governing devices for internal combustion engines.

In accordance with my invention, the speed of the engine is controlled by automatically controlling the flow of mixture from the carburetor to the engine so that when the engine speed exceeds the predetermined normal the supply of mixture or motive fluid will be reduced, thereby reducing the speed of the engine.

The objects of the invention are to provide a governor of this class, in which a controlling valve is actuated by a part of the motive fluid, to control the flow of all of the fluid and also to provide an indicating mechanism which will show the positions of the control valve and indirectly show the power of the engine and loss of fuel through leakage of pistons, valves, etc.

The invention is illustrated in the accompanying drawings in which—

Figure 1 is a side elevation of a conduit connecting a carburetor with the intake pipe of an internal combustion engine; Fig. 2 is a longitudinal section of the same; Fig. 3 is a transverse section on the line 3—3 of Fig. 2 and Fig. 4 is a section on the line 4—4 of Fig. 3.

Referring to the drawings, 10 indicates the section of the conduit which is connected with the carburetor, and 11 the section which is connected with the intake pipe of the engine. The section 10 of the conduit is provided with the usual throttle valve 12 whereby the supply of motive fluid may be manually controlled. Between the sections 10 and 11 is a section 13 in which a balanced butterfly valve 14 is arranged. Extending upwardly from the butterfly valve 14 is a partition 15, which may be secured in the section 13 in any suitable manner, and the upper part of which is corrugated, as shown at 16, and curved substantially about the axis of a shaft 17 on which a grid valve 18 is secured. The partition 15 divides the current of motive fluid into two streams, and the corrugations at 16 have a tendency to

create a whirlpool in the stream of fluid at the outer edge of the valve 18, this whirlpool reacting on the edge of the valve and tending to make the flow more uniform and also prevent "surging" motion of valve.

Mounted on the valve 18 is a grid 19 having lugs 20 to which a link 21 is pivotally connected. The link 21 has a fixed fulcrum at 22, and is provided with a laterally projecting lug or toe 23 which is adapted to engage the end of an adjustable screw 24 for the purpose of limiting the swinging movement of the valve 18 and thus limit the speed of the engine. It will be seen that as the valve 18 swings upwardly from the position shown in Fig. 2, the grid 19 will be moved toward the partition 15, and the ports through the valve and grid will be thrown out of register and thus restrict the opening through the valve. The valve 18 is connected with the valve 14 by means of a link 25, so that the valve 14 is swung from the position indicated in Fig. 2 as the valve 18 rises. The valve 14 has an opening 26 which permits a restricted flow of the motive fluid through the valve 18 when the valve 14 is in the closed position, in which it is indicated in dotted lines in Fig. 2.

A spiral spring 27 has its inner end connected with the squared end 28 of the shaft 17, and its outer end connected with a rotatable cap 29 having a bearing 30 in the wall of the section 13 of the conduit. The spring resists the upward swinging movement of the valve 18, and the tension of the spring may be adjusted by rotating the cap 29, the cap being held in any position to which it is adjusted by means of a detent 31 which is adapted to engage the notches 32 in the outer surface of the cap. The detent 31 is held in engagement with the notches 32 by means of a spring 33, as clearly shown in Fig. 4.

On the exterior of the section 13 of the conduit there is secured a dial 34 having scales 35 thereon for indicating the position of the valve 18 and, indirectly, the power of the engine. A hand 36 is pivoted at 37 and has connected therewith a pinion 38 which meshes with a gear segment 39 on the shaft 17, so that as the shaft 17 rotates in accordance with the movements of the valve 18, the hand 36 will be moved over the scales 35.

A casing 40 is arranged to cover the screw 24 and also the cap 29 in order to prevent

unauthorized adjustment of these parts. The casing 40 is pivotally connected with the section 13 of the conduit, at 41, and is secured by means of a padlock or other suitable device 42.

5 In the operation of the device the motive fluid passing through the conduit is divided into two streams, one passing on the left hand side of the partition 15 and the other 10 on the right hand side thereof, as seen in Fig. 2. The flow on the right hand side of the partition 15 causes the valve 18 to be lifted, and the movement of the grid 19 on the valve restricts the opening through the 15 valve and thus regulates the flow of the motive fluid. The valve 14 is also swung toward the closed position, as the valve 18 rises, so that the valve 14 controls the flow on both sides of the partition 15. The rate 20 of flow of motive fluid will be in proportion to the speed of the engine, and when the engine speed becomes excessive, the velocity of the motive fluid will be so great that the valve 18 will be carried to the limiting 25 position in which the lug 23 engages the end of the screw 24. The opening 26 permits the motive fluid to flow on the right hand side of the partition 15 when the valve 14 reaches the closed or nearly closed position.

35 The power developed by the engine will ordinarily be in proportion to the amount of motive fluid supplied thereto, and the position of the valve 18 will, indirectly, indicate the rate at which the motive fluid is being supplied to the engine, and therefore, the position of the hand 36, which at all 40 times corresponds with the position of the valve 18, will also indicate the power developed by the engine. The spring 27 may be adjusted so that the fuel will be supplied to the engine at the required rates to produce desired speeds under given condition of load and the graduations 35 made to indicate the 45 normal speeds for different positions of the valve 18. In case the engine develops leaky pistons or valves, the speed will not accord with that indicated and therefore the condition of the engine will be apparent.

50 Having thus described the invention, what I claim and desire to secure by Letters Patent, is:

1. In a device of the class described, the combination of a divided conduit, a valve in one branch of said conduit adapted to be moved by the flow of fluid, and means actuated by said valve for controlling the flow through the other branch of the conduit.

60 2. In a device of the class described, the combination of a divided conduit, a valve in one branch of said conduit adapted to be moved by the flow of fluid, means coöperating with said valve to restrict the opening therethrough in accordance with increases in the velocity of flow, and means actuated

by said valve for controlling the flow through the other branch of the conduit.

3. In a device of the class described, the combination of a conduit having a longitudinal partition therein to divide the flow 70 into two streams, a valve on one side of said partition, adapted to be moved by the flow of fluid, and a valve operatively connected with said valve and arranged to control the flow on the other side of the partition. 75

4. In a device of the class described, the combination of a conduit having a longitudinal partition therein to divide the flow 80 into two streams, a valve, on one side of said partition, adapted to be moved by the flow of fluid, means coöperating with said valve to restrict the opening therethrough in accordance with increases in the velocity of flow, and a balanced valve operatively connected with said valve and moved thereby 85 to control the flow on the other side of said partition.

5. In a device of the class described, the combination of a conduit having a longitudinal partition therein to divide the flow 90 into two streams, a valve, on one side of said partition, adapted to be moved by the flow of fluid, means coöperating with said valve to restrict the opening therethrough in accordance with increases in the velocity of 95 flow, and a balanced valve operatively connected with said valve and moved thereby to control both of said streams.

6. In a device of the class described, the combination of a conduit having a longitudinal partition therein to divide the flow 100 into two streams, a grid valve on one side of said partition, adapted to be moved by the flow of fluid, a grid mounted on said valve and movable therewith, means for moving said grid relatively to said valve to restrict the opening through the valve in accordance with increases in the velocity of 105 flow, and a valve operatively connected with said grid valve and moved thereby to control the flow on the other side of said partition. 110

7. In a device of the class described, the combination of a conduit, having a longitudinal partition therein to divide the flow 115 into two streams, a grid valve on one side of said partition, adapted to be moved by the flow of fluid, a grid mounted on said valve and movable therewith, means for moving said grid relatively to said valve to restrict the opening through the valve in 120 accordance with increases in the velocity of flow, a balanced valve arranged in said conduit and adapted to control both of said streams, and means connecting said grid valve and said balanced valve. 125

8. In a device of the class described, the combination of a conduit having a longitudinal partition therein to divide the flow 130 into two streams, a grid valve on one side of said partition, adapted to be moved by

the flow of fluid, a grid mounted on said valve and movable therewith, means for moving said grid relatively to said valve to restrict the opening through the valve in accordance with increases in the velocity of flow, and a balanced valve arranged in said conduit and adapted to control both of said streams, said balanced valve having an opening therein permitting a restricted flow through said valve when the balanced valve is in closed position.

9. In a device of the class described, the combination of a conduit, a grid valve pivotally arranged in said conduit and adapted to be swung by the flow therethrough, a grid mounted on said valve and movable there-

with, a link connected with said grid and having a fixed fulcrum, and means adapted to engage said link to limit the swinging movement of said valve.

10. In a device of the class described, the combination of a conduit, a grid valve pivotally arranged in said conduit and adapted to be swung by the flow therethrough, a grid mounted on said valve and movable therewith, a link connected with said grid and having a fixed fulcrum, and an adjustable screw adapted to engage said link and limit the swinging movement of said valve.

In testimony whereof I affix my signature. 30

EDWARD C. NEWTON.
